UNITED STATES PATENT OFFICE

GEORGE ZINT, OF WAPAKONETA, OHIO

SIGNAL

Application filed July 5, 1929. Serial No. 376,192.

This invention relates to a railroad crossing signal, the general object of the invention being to provide means for not only causing a train to operate signal means placed adjacent the crossing to warn persons at the crossing that a train is approaching, but also to provide means whereby one can tell how close the train is to the crossing so that he will know whether or not he has time to safely 10 pass over the track.

Another object of the invention is to provide both a visual signal and an audible one, both of which are operated by a train approaching the crossing.

15 This invention also consists in certain other features of construction and in the combination and arrangement of the several parts, to be hereinafter fully described, illustrated in the accompanying drawings and specifically pointed out in the appended claims.

20 In describing the invention in detail, reference will be had to the accompanying drawings wherein like characters denote like or corresponding parts throughout the several 25 views, and in which:

Figure 1 is an elevation of a track at a crossing, showing the invention in use.

Figure 2 is a plan view of Figure 1.

20 Figure 3 is a vertical sectional view through the signal carrying casing.

Figure 4 is a vertical sectional view through the casing, this view being taken at right angles to Figure 3.

35 Figure 5 is a view, partly in section, of one of the track members.

Figure 6 is a top plan view of Figure 5.

Figure 7 is a section on line 7-7 of Figure 6.

40 Figure 8 is a diagrammatic view of the circuits.

In these drawings, the letter A indicates one track and the letter B the other track. A plurality of switch boxes 1 is located adjacent the outside rail of each track, these boxes 45 being spaced apart, a certain distance. I prefer to space the boxes 100 feet apart, and the one nearest the crossing may be 100 feet from the crossing. A shaft 2 is journaled in each box and extends therefrom and an arm 3 is connected with the outer end of each

shaft. This arm extends upwardly at an angle toward the crossing and each arm is composed of a lower part 3' which is hollow, and an upper part 3'' which telescopes the lower part, with a rod 4 connected with the upper part and extending into the lower part, where it is formed with a head which is engaged by a spring 5 in the lower part which holds the upper part in raised position. Thus when a train approaches the crossing, its 55 wheels, striking the arms, will lower the same and thus rock the shafts, but a train leaving the crossing will simply engage the top part of each arm and depress the same against the action of the spring 5 so that the arm will not 60 rock the shaft. A substantially semi-circular member 6 is fastened to the inner end of each shaft and a spring 7 is connected to one part of this member and to a part of the box, this 65 spring tending to hold the shaft with the arm 3 in raised position. An insulated contact 8 is carried by another part of the member 6 and when the shaft is rocked by the passage 70 of a train toward the crossing, this contact 75 will strike a spring switch arm 9 and cause it to engage a second arm 10 and thus close a circuit 11 of a lamp 12 and a pair of magnets 13. These magnets attract an armature 14 to which is attached a bell hammer 15 of a 80 large bell 16. This bell is so arranged that it will be engaged by the hammers of all the magnets. This bell and the sockets 17 of the 85 lamps are arranged in a circular casing 18 mounted on a post 19 located adjacent the crossing. The lamps extend through holes 90 formed in the periphery of the casing and each lamp is covered by a cap-like globe 20 which is detachably connected with the casing.

The track members for each track are electrically connected with the lamps and magnets, as will be seen from Figure 1.

From the foregoing it will be seen that as a train approaches the crossing, it will first strike the arm farthest from the crossing and thus close the switch of one of the lamp circuits and the magnets in said circuit so that one of the lamps will be lighted and the bell will be struck by one of the hammers. Then 95 the train will engage the next arm and thus 100

another lamp will be lightened and the bell struck by another hammer and this operation will be repeated until all the lamps have been lighted progressively. Thus one can tell by 5 watching the lamps how far a train is from the crossing and whether or not he has time to pass over the same.

An extra lamp 21 is arranged at the top of the casing and is connected by the conductor 10 22 with the battery C or other source of supply. This lamp remains lighted all the time and serves to indicate the signal device.

It is thought from the foregoing description that the advantages and novel features of 15 the invention will be readily apparent.

It is to be understood that changes may be made in the construction and in the combination and arrangement of the several parts, provided that such changes fall within the 20 scope of the appended claims.

What I claim is:—

1. A railroad crossing signal comprising a group of lamps, a bell, a plurality of hammers for the bell, magnetic means for each 25 hammer, a circuit for each lamp and magnetic means and means for successively closing the circuits by a train approaching the crossing.

2. A railroad crossing signal comprising 30 a group of lamps, a bell, a plurality of hammers for the bell, magnetic means for each hammer, a circuit for each lamp and magnetic means, means for successively closing the circuits by a train approaching the crossing, such means comprising a plurality of 35 switches arranged along the track in front of the crossing and an arm for operating each switch and engaged by a part on a train as the train approaches the crossing.

40 3. A railroad crossing signal comprising an upright arranged adjacent the crossing, a circular casing on the upright, a plurality of lamps carried by the casing, a bell in the casing, a plurality of hammers for the bell, 45 magnetic means for operating each hammer, a circuit for each lamp and magnetic means and a plurality of switches arranged along the track in front of the crossing, each switch being arranged in a circuit and means for 50 closing the switches by a train approaching the crossing.

In testimony whereof I affix my signature.

GEORGE ZINT.
